(57) **CLAIM**

The ornamental design for an adjunctive sheet for sewing machines, as shown and described.

DESCRIPTION

FIG. 1 is a front view of an adjunctive sheet for sewing machines;

FIG. 2 is a top view thereof;

FIG. 3 is a right-side view thereof;

FIG. 4 is a left-side view thereof;

FIG. 5 is a rear view thereof; and,

FIG. 6 is a bottom view thereof.

The solid black shading shown in the background in the front view represents a contrast in color between the background and the circle pattern.
